(57) **CLAIM**

The ornamental design for a tire, as shown and described.

DESCRIPTION

FIG. 1 is a front elevation view of a tire showing our new design;

FIG. 2 is a front, left side perspective view thereof;

FIG. 3 is a left side view thereof, the right side view being the mirror image thereof;

FIG. 4 is a partial front elevational view taken from FIG. 1 and shown in an enlarged scale; and,

FIG. 5 is an enlarged fragmentary front view showing laterally adjacent right cleats and a channel therebetween.

1 Claim, 5 Drawing Sheets
